UNITED STATES PATENT OFFICE

CHARLES G. SCHOTT, OF ST. LOUIS, MISSOURI

DESIGN FOR A HEATING STOVE

Application filed October 17, 1929. Serial No. 33,073. Term of patent 14 years.

To all whom it may concern:

Be it known that I, CHARLES G. SCHOTT, a citizen of the United States, and a resident of the city of St. Louis, and State of Missouri, have invented a new, original, and ornamental Design for a Heating Stove, of which the following is a specification, reference being had to the accompanying drawing, forming part thereof.

The drawing is a front elevation, in perspective, of a heating stove showing my new design.

I claim:

The ornamental design for a heating stove, substantially as shown.

CHARLES G. SCHOTT.
